UNITED STATES PATENT OFFICE.

CHARLES SUITER, OF BILLINGS, MONTANA.

SUPERFINE-GOLD EXTRACTOR.

1,164,677.

Specification of Letters Patent. Patented Dec. 21, 1915.

Application filed July 24, 1914. Serial No. 852,898.

To all whom it may concern:

Be it known that I, CHARLES SUITER, a citizen of the United States, residing at Billings, in the county of Yellowstone and State of Montana, have invented certain new and useful Improvements in Superfine-Gold Extractors, of which the following is a specification.

This invention relates to the general subject of extracting machines, or amalgamators, for recovering precious metals from their ores, and has specially in view a novel and practical construction of machine of this character which possesses special utility as a superfine gold extractor, that is to say, a machine having means for recovering very small and light particles of metal, such as float-gold, invisible gold, rust-gold, and other like forms or conditions of the metals that are generally carried off and lost in the debris of a gold mining plant.

In carrying out the foregoing general object, the present invention also has in view an extracting machine of the amalgamator type which may be utilized to great advantage as one of the extracting units of a placer mining system.

With these and other objects in view which will be apparent to those familiar with the art, the invention consists in the novel construction, combination, and arrangement of parts herein fully described, illustrated, and claimed.

Though susceptible of structural modification without departing from the invention, a preferred and practical embodiment thereof is shown in the accompanying drawings, in which—

Figure 1 is a vertical sectional view of superfine extracting machine embodying the improvements contemplated by the present invention. Fig. 2 is an enlarged elevational view illustrating the form and mounting of one of the individual amalgam plates. Fig. 3 is an enlarged fragmentary sectional view illustrating more clearly the structural characteristics and relation of a pair of the amalgam plates in connection with the stand pipe with which they are associated.

Like reference characters designate corresponding parts in the several figures of the drawings.

As above indicated, the preferable application of the present invention is as one of the units of a placer mining system, wherein the washings from the boulders and gravel

are subjected to a settling operation involving the running off of water carrying metal-bearing material in suspension, that is, disintegrated clay in suspension, as well as small light particles of metal, such as float-gold, invisible gold, rust-gold, and other forms of the metal or metal bearing substances that are generally carried off and lost in the debris of the plant. Accordingly, the improved extracting machine of the present application is characterized as a superfine extractor, and the same primarily includes in its organization a feeder stand-pipe 1, whose upper end is extended through a water tight stuffing box 2 and communicates with the interior of a supply sluice 3 through which the metal-charged water is conducted to the line of extracting machines, only one of which is deemed necessary for purposes of illustration in this case.

The flow of water, carrying the metals and metal-bearing substances in suspension, is checked adjacent the upper end of the stand-pipe 1 by means of a baffle plate 4 arranged transversely of the supply sluice, but of less height than the sluice so as to permit an overflow of water to pass beyond to the next succeeding extracting machine. The stand-pipe which is thus supplied with a column of the metal-charged water is supported in a vertical or upright position and is rotatably mounted within the stuffing box 2, the lower end of the stand-pipe being stepped in a holding socket 5 which is bolted or otherwise rigidly fastened to the central upper part of a turn-table 6.

The turn-table is arranged to loosely and horizontally rotate within a retaining buffer or buffers 7 and rides upon a series of supporting rollers 8 journaled in suitable brackets 9 upon a base frame 10. To provide for taking up wear and maintaining a steady rotation of the turn-table 6, the latter has fitted to the under side thereof a circular track plate 11 bearing on these supporting rollers. Movement is imparted to the turn-table by any suitable driving means which may conveniently consist of a power driven drive shaft 12 supported over the base frame 10 and carrying a friction driving pulley 13 frictionally engaging the under side of the turn table and shiftable radially thereof according to the speed of rotation desired for the turn-table. Any conventional shifting device, as indicated generally by the reference number 13^a, may be employed for

changing the position of the driving pulley 13.

The revolving turn-table carries therewith an amalgamating unit consisting primarily of the feeder stand-pipe 1 and a concentric series of superposed amalgam plates 14 adjustably fitted to and carried with the stand-pipe in its rotation of the turn-table. All of the superposed amalgam plates are similar in construction and are of the same form, that is, each of said plates is of a frusto-conical shape so that the same slopes downwardly from its point of attachment to the stand-pipe to its outer spilling edge or periphery. It will also be observed that by reason of the frusto-conical forms of the several amalgam plates, the same bear a nested relation one within the other, but necessarily spaced a sufficient distance apart to permit each of the same to carry out the amalgamating function thereof, and another distinctive feature in the general arrangement of these amalgam plates is that the same are of a graduated size, the same being successively of a diminishing diameter from the uppermost to the lowermost plates of the unit.

Referring more particularly to the mounting of the individual amalgam plates and their relation to the stand-pipe and the other plates, it will first be noted that the said plates are of circular form and pierced at the centers for the reception of the stand-pipe, and their inner edges have rigidly fitted thereto the angle-holding collars 15, the angle formation of these collars being produced by providing the same at their lower edges with the out-turned securing flanges 16 to which the plates 14 are permanently or rigidly united by means of the rivets or equivalent fastenings 17. The upright or sleeve portion of each collar snugly, though slidably, receives the stand-pipe 1 and is securely and adjustably held thereon by means of a plurality of locking set screws 18 passing through the collar, and preferably having inner burred ends 19 impinging on the stand-pipe.

The upright or sleeve portion of each plate-holding collar 15 is also provided therein with a plurality of distributing ports 20 adapted to communicate with feeding ports 21 in the stand pipe to provide means for receiving and distributing the metal charged water over the sloping upper side of the amalgam plate. A further function of each plate holding collar 15 is as a carrier for an annular baffle hood 22, extending entirely about the collar and provided with an upstanding neck flange 23 embracing the collar and receiving the said screws 18 which thereby support the hood 22 in operative position. The said hood is also provided at its outer edge with a depending deflecting flange 24 lying beyond and masking the dis-

tributing ports 20 so as to compel the metal-charged water to be deflected in the first instance directly onto the crowned portion of the amalgam plate.

In order to secure the necessary rigidity for the amalgamating unit and its firm support upon the turn-table, in connection with the stand-pipe, a plurality of upright brace bars 25 are employed. These brace bars are provided at their lower ends with attaching feet 26 adjustably held by the screws 27 or equivalent fastening means to the turn-table, and extend upwardly against the outer peripheral edges of the entire series of amalgam plates. Each brace bar is rigidly connected to said outer peripheral edge portion of each amalgam plate by means of bolts or equivalent fastenings 28 passing through the depending flanges of angle irons 29 whose upper flanges are rigidly secured by rivets 30 or otherwise, to the under side of the amalgam plate contiguous to the outer peripheral edge thereof. To complete the brace bar fastenings, there is preferably employed an outer circular retaining band 31 bolted to the entire series of brace bars and extending about the upper end portions thereof. It will thus be seen that all of the amalgam plates are rigidly held in their spaced relation while at the same time being rigidly and firmly connected with the turn-table so that all parts of the amalgamating unit are held for a steady and regular rotation with the turn-table.

A cleaner spray pipe 32 is arranged concentrically within the feeder stand-pipe 1 and is connected with a suitable source of water supply. This spray pipe is provided at intervals therein with annular series of jet openings 33 arranged in a horizontal plane of the ports 20 and 21 and adapted to jet streams of water through such ports to prevent the same from being clogged or obstructed with sand or sediment, and at the same time assist in the discharge through the said ports 21 should the metal-charged water in the stand-pipe be largely impregnated with sand or sediment.

It will have been observed from the foregoing description that the metal-charged water passing out of the stand-pipe and through the various ports 20 is caused to spread in a thin film over the series of amalgam plates, and this feeding operation is assisted by the action of the water jets from the jet openings 33, as above explained. As the water flows outward and downward on the amalgam plates, it would have a tendency to run in streams, but this is prevented by the rotation of the amalgamating unit with the turn-table thereby causing the water to spread in a thin film over the entire surface of each amalgam plate, thus causing every particle of metal in the water to come in contact with the amalgam plates, and

thereby successfully causing the extraction and recovery of the small light particles of gold, such as float-gold, invisible gold, rust gold, and other forms of the metal which 5 heretofore have been very difficult of recovery.

The water spilling off of the outer peripheral edges of the amalgam plates, drips or falls into a circular run-off trough 34 arranged 10 about the turn table, and which trough carries the water off to the settling reservoirs.

If it becomes desirable to vary the size of the openings or ports 21 to adjust the volume 15 of discharge through such ports onto the amalgam plates, this may be accomplished by loosening the various set screws 18 and the bottom fastenings 26 for the brace bars 25, and then slightly rotating the connected 20 amalgam plates upon the stand-pipe, after which the same may be held in the newly set position by retightening the screws 18 and securing the fastenings 26 in a new position.

25 Various changes in the form, proportion and minor details of construction may be resorted to without departing from the spirit or sacrificing any of the advantages of the invention.

30 I claim:

1. An extracting machine including, in combination, a circular run-off trough, a rotatable feeder stand-pipe having feeding ports, and a concentric series of superposed 35 conical amalgam plates rigidly connected at their apices with the stand-pipe and sloping outwardly and downwardly therefrom, said amalgam plates being arranged to receive the metal-charged water from the stand-pipe, and of diminishing diameters from the uppermost to the lowermost plates of the series, all of said amalgam plates having 40 their spilling edges lying in the vertical plane of the run-off trough.

45 2. An extracting machine including, in combination, a turn-table, a circular run-off trough, a ported feeder stand-pipe carried by the turn-table, and a concentric series of superposed conical amalgam plates having 50 an adjustable rigid connection at their apices with the stand-pipe and sloping outwardly and downwardly therefrom, the outer spilling edges of all of the amalgam plates discharging into the said run-off trough.

55 3. An extracting machine including a feeder stand-pipe having separate sets of

feeding ports, a concentric series of superposed conical amalgam plates, a holding collar for each amalgam plate having a fastening connection with the stand pipe and provided with distributing ports registering with a set of the feeding ports in the stand-pipe, and means for rotating the stand-pipe and series of amalgam plates as a unit. 60

4. An extracting machine including a 65 feeder stand-pipe provided with a plurality of sets of feeding ports, a concentric series of superposed conical amalgam plates, a holding collar for each amalgam plate having a rigid connection therewith at its inner 70 edge portion, and also having an adjustable fastening connection with the stand-pipe, each holding collar being also provided with a series of distributing ports registering with a set of feeding ports in the stand-pipe, 75 and means for rotating the stand pipe and amalgam plates together as a unit.

5. An extracting machine including a 80 feeder stand-pipe provided with a plurality of sets of feeding ports, a concentric series 85 of superposed conical amalgam plates, there being one amalgam plate arranged below and receiving the discharge from one set of the feeding ports, a baffle hood arranged over the inner edge portion of each amalgam plate and masking the discharge of the feeding ports therefor, and means for rotating the stand-pipe and amalgam plates together as a unit.

6. An extracting machine including a 90 feeder stand-pipe provided with a plurality of sets of feeding ports, a concentric series of superposed graduated conical amalgam plates, holding collars secured to the inner edge portions of said plates, and each of 95 which collars is provided with a plurality of distributing ports registering with a set of the feeder ports in the stand-pipe, a baffle hood arranged over the inner edge portion of each amalgam plate beyond the feeding 100 and distributing ports therefor, fastening means for supporting the holding collars on the stand-pipe, said fastening means supporting the baffle hood, and means for rotating the stand-pipe and amalgam plates 105 together as a unit.

In testimony whereof I hereunto affix my signature in the presence of two witnesses.

CHARLES SUITER.
